(57) CLAIM

The ornamental design for a blood pressure reducing device, substantially as shown and described.

DESCRIPTION

FIG. 1 is a perspective view of the blood pressure reducing device;

FIG. 2 is a rear view of the blood pressure reducing device;
FIG. 3 is a front view of the blood pressure reducing device;
FIG. 4 is a right side elevational view of the blood pressure reducing device;

FIG. 5 is a left side elevational view of the blood pressure reducing device;

FIG. 6 is a top plan view of the blood pressure reducing device; and,

FIG. 7 is a bottom plan view of the blood pressure reducing device.
